ETCHING MACHINE

Charles S. Martz, Aurora, Mo., assignor to The Tasope
Company, Aurora, Mo., a partnership

Application September 30, 1957, Serial No. 47,922

Term of patent 14 years

(Cl. D55—1)

FIG. 1.

FIG. 2.

FIG. 3.

FIG. 4.

FIG. 5.

Fig. 1 is a top plan view of an etching machine showing my new design;

Fig. 2 is a front elevational view thereof;

Fig. 3 is a rear elevational view thereof;

Fig. 4 is a side elevational view thereof; and

Fig. 5 is an elevational view of the side opposite to that shown in Fig. 4.

I claim:

The ornamental design for an etching machine, as shown.
